VIAL OPENER

Albert Smith, 27716 Havana Ave., Hayward, Calif.
Filed Nov. 13, 1963, Ser. No. 323,329
8 Claims. (Cl. 225—103)

The present invention relates to a device for opening sealed glass containers. More specifically, the invention relates to opening sealed vials. Even more specifically, the invention relates to opening sealed glass vials having a thin walled bulb portion and a thick walled tubular stem portion.

Vials of the foregoing type are used as specialized chemical containers. Utilization of such vials in the lyophilizing or freezing-drying of microorganisms exemplifies a particular specialized use of such vials.

Freeze-drying is a fast expanding technique which has many beneficial advantages. One such advantage lies in the preservation of microorganisms in an inert state for long periods of time with only slight loss, if any, of the microbial activity of the organism. Basically, the process involves the simultaneous application of controlled temperature and pressure conditions. With specific reference to the use of lyophilizing vials, that process will now be described in more detail.

A lyophilizing vial is a glass tube which has been blown into a bulb at one end. The bulb can be blown into various sizes. As the bulb size is increased the wall thickness of the bulb decreases. The stem portion remains of original thickness. For this reason, the bulb portion is much more delicate than the stem portion. A typical tube having an outside diameter of 10 mm. has a 2 mm. wall. The stem portion is typically 100 mm. in length. In the lyophilizing process, a solution of the material to be preserved is deposited into a lyophilizing vial, usually filling the bulb of the vial to about one half its capacity. The bulb portion is next dipped into a liquid freezing solution and the stem twirled between the fingers, thereby quickly freezing the material into a shell around the inside of the bulb. When freezing is complete, the vial is immediately placed on a vacuum apparatus. When complete dehydration of the material has taken place, and it is in the form of a solid, usually a powder, the lyophilizing process is complete. The vial is now sealed, while still under vacuum, in the following manner:

Flame from a torch is applied to the upper portion of the stem, away from the bulb, as close to the vacuum apparatus as possible, and the stem is melted at this point. This seals the vial under a partial vacuum, leaving the stem from thirty mm. to seventy mm. long, with a small tip protruding where the melting of the stem took place.

The re-opening of those vials is a dangerous and difficult procedure as it is accomplished as follows:

A file cut is made on the stem of the vial, and the stem broken at the file cut, using the fingers and thumbs as levers. The vial is usually wrapped in toweling before the stem is broken, but due to the great pressure needed to break the thick stem, and the unavoidable contact with the thin shelled bulb, this proves to be inadequate protection, and badly cut hands have resulted. The cuts are doubly dangerous because of direct exposure to any numerous toxic microorganisms normally stored in the vials. After the stem is broken, the contents of the vial are rehydrated with a suitable material and used immediately for whatever purpose intended.

It is an object of this invention to overcome the aforementioned disadvantages by providing a device for safely and efficiently opening glass vials. It is a further object of the invention to provide such a device essentially free from contamination.

These and other objects and advantages which will become apparent from the present specification are achieved according to the present invention which provides a device for holding a sealed vial and hammer means to cleanly break a stem thereof under sterile conditions.

In the drawings, in which a preferred embodiment is illustrated,

FIG. 1 is a side elevation, in section taken along the lines I—I of FIGURE 2, of a device according to the 10 present invention;

FIG. 2 is a rear elevation, in section taken along the lines II—II of FIGURE 1, of the device of FIGURE 1;

FIGURE 3 is a front elevation of the device shown in FIGURE 1;

FIGURE 4 is a sectional view of a portion of the front outer wall of the device of FIGURE 1; and FIGURE 5 is a side view of an eccentric hammer member shown mounted in the device shown in FIGURES 1, 2 and 3.

In the drawings, wherein like numerals refer to like 20 parts, a housing, generally designated as 1, comprises front wall 2, rear wall 3, side walls 4, top wall 5 and base 6. A slanted portion 7 joins front wall 2 and top wall 5. A container 8 having wall 9 and bottom 10 is inserted inside housing 1 such that rear wall 11 forms 25 the lower portion of the rear housing wall. A sterilizing solution, such as benzalkonium chloride in water, is present in container 8. Benzalkonium chloride is a mixture of alkyldimethylbenzylammonium chlorides well known as a germicide. Sterilizing liquids are well known 30 in the art per se, and any and all of the solutions are useful in the present invention. The container 8 may be of any suitable material resistant to attack by the sterilizing solution employed. The container has a handle 12 and is removable from the housing by merely 35 pulling the container rearward. A latch and/or seal can be provided to secure the container within the housing and form a tight enclosure.

The construction of the housing 2 may be of any suitable 40 rigid material including transparent plastic such as Lucite or Plexiglas, registered trademarks for polymethyl methacrylate. Screws or other fasteners and/or adhesives may be used to join the walls etc., of housing 2. In the event that housing 2 is fabricated from metal, brazing or welding techniques may be employed in fabrication.

As shown most clearly in FIGURE 4, front wall 2 has an aperture therein defined by edge 13. This aperture defines an inclined passageway, best seen in FIGURE 1, through front wall 2. A vial 14 of the type used in the aforementioned freeze-drying process, is depicted inserted 50 through passageway in FIGURE 1. As shown therein, the vial has a bulb portion 15 and a stem portion 16. The passageway is of a size larger than vials to be opened, and a rigid annular adaptor 17 is utilized to engage the surface of the passageway and the outside wall 55 of stem 16. As can be seen in FIGURE 4, adaptor 17 is keyed at 18' to prevent rotation in the passageway. The adaptor is slotted at 19 to permit entry of tip portion 20 of a vial stem. Tip portion 20 results from the flame sealing step aforementioned.

A retaining member 18 is rotatably secured to front 60 wall 2 and has a cup-shaped portion registerable with the hole defined by edge 13 to engage the bulb portion of a vial and thus hold the vial firmly in place for the opening operation. The cup-shaped clamp has an over-sized cup lined with a soft material and is thus adaptable to various bulb sizes. Various other retaining means, such as spring biased members, can be utilized for this function.

A hammer member 21 is rotatably mounted on shafts 22 70 within housing 2. The hammer is a heavy eccentric cam having a hollow central portion 23 to permit the full insertion of long vial stems within the housing. This

feature is most clearly shown in FIGURE 1 wherein stem 16 is shown in dashed lines where inside the center of hollow portion of hammer 21. Shafts 22 are shown secured to hammer 21 by screw threads, but may be secured in any convenient manner. The shafts are journaled through side walls 4. Any bearing arrangement, such as bushings, can be employed to assure free rotation of shafts 22. To turn the shafts 22, and cause rotation of hammer member 21, a hand wheel 24 is secured to the outer end of a shaft 22. Other lever means can, of course, be employed as a substitute for hand wheel 24.

A detailed description of the operation of the device, including experimental determination of contamination-free operation, is as follows:

Pure cultures of two separate organisms, chosen because of their vastly different colonial morphology as seen on a nutrient agar plate were prepared. Twelve hour broth cultures were used. Each culture was distributed in 1 ml. amounts into 10 lyophilizing vials having a 5 ml. bulb capacity. The twenty vials thus prepared were then lyophilized completely according to the aforementioned process. The present device was thoroughly cleaned with a 1:1000 aqueous benzalkonium chloride solution. A swab of the inside of the apparatus was streaked onto nutrient agar to provide a control for determining comparative sterility. After incubation for 24 hours at 37° C., this plate showed no growth.

The twenty bulbs prepared were then opened with the present device. Using a first vial from one of the two cultures, the stem was inserted through an adaptor keyed in the passageway and having an inside diameter only slightly larger than the outside diameter of the vial stem. The cup-shaped retaining clamp was then swung into position to firmly hold the vial in the position shown in FIGURE 1. Hammer member 21 was rotated rearwards, out of the way of the vial stem during insertion. Conveniently, a stop of any suitable design can be employed to arrest the rearward motion of hammer 21 such that it remains locked in the upright position during vial insertion. Alternatively, the hammer may merely rest against rear wall 3 or a projection thereon. If the walls of the device are opaque, handle 24 may be marked to show hammer position. The adaptor is chosen according to the vial stem size. Thus, with one device and a suitable range of adaptor sizes, any vial can be opened by the present device.

Because the passageway is inclined to the horizontal, the vial is likewise inclined. This prevents spillage of the vial contents.

To facilitate breakage, vial stem 16 should be scored as by a file. The vial is scored at a position such that the score is just inside the front wall 2.

Hammer member 21 is of a heavy rigid construction such as of stainless steel. Once the vial was inserted, hand pressure on wheel 24 causes hammer 21 to strike vial stem 16. A slight constant pressure is exerted on the stem by the hammer, as the vial breaks clean at the score mark. The upper portion of the stem falls into sterilizing container 8. To ensure elimination of cross contamination, the container may be filled such that the hammer may be dipped into the sterilizing solution, although this feature is not necessary as shown by the present experimental results. The opened vial was then removed from the housing.

A second vial, selected from the second culture was then opened. The ingredients of the opened bulb was suspended in 5 ml. of nutrient broth. It was then streaked on a nutrient agar plate. After 24 hours of incubation at 37° C., the specimen grew on its agar plate with no evidence of contamination by organism from the previously open vial. The inside of the apparatus was swabbed and an agar plate prepared. After the specified incubation, no growth was evident. These steps of checking each specimen and the inside of the housing were

repeated for each of the remaining eighteen bulbs, alternating each time between cultures. No cross contamination or contamination of the device was indicated after 24 hours incubation at 37° C.

Hammer member 21 is positioned such that a peripheral edge thereof passes in close proximity to front wall 4 at the inner end of the passageway. By this feature, the stem is caused to be struck close to the position supported by adaptor 17.

I claim:

1. A device for opening sealed glass containers having a tubular stem portion comprising a housing having a stationary supporting member including an aperture therein defining a passageway inclined at an angle to the horizontal, a rigid annular adaptor member releasably secured within said aperture, rotatable hammer means mounted within said housing and rotatable about an axis parallel to the diameter of said aperture such that the free end thereof passes in close proximity to the hole defined by the inner end of said adaptor to strike a stem portion of a glass container protruding through said hole and into said housing, and means to rotate said hammer means.

2. A device for opening sealed vials comprising a housing having front wall and two side walls, said front wall including an aperture defining a passageway inclined at an angle to the horizontal, a rigid annular adaptor member releasably secured in said aperture, an eccentric massive hammer member secured to shaft means rotatable about an axis parallel to said front wall, said shaft means being positioned such that the remote end of said eccentric hammer member is rotatable into close proximity with the opening defined by the inner end of said adaptor to strike a stem portion of a vial protruding through said hole and into said housing, and means to rotate said eccentric hammer member.

3. A device for opening sealed glass containers having a tubular stem portion comprising a housing having a stationary supporting member including an aperture therein defining a passageway inclined at an angle to the horizontal, rotatable hammer means mounted within said housing and rotatable about a horizontal axis parallel to the plane of said stationary supporting member such that a peripheral portion thereof is moveable in close proximity to a hole defined by the inner end of said aperture, means to rotate said hammer means, and means to supply a sterilizing liquid to said hammer means.

4. A device as claimed in claim 3 wherein said means to supply sterilizing liquid to said hammer means comprises a container for sterilizing liquid disposed such that at least a portion of said hammer means is rotatable therewith.

5. A device for opening glass vials having a straight-walled tubular stem portion comprising a housing having a vertical front wall and two vertical side walls, said front wall including an aperture therein defining a passageway inclined at an angle to the horizontal, a rigid annular adaptor releasably secured within said aperture, an eccentric hammer member mounted within the housing by shaft means, said shaft means comprising two separate shafts each mounted for rotation in a side wall along a common horizontal axis parallel to said front wall, said eccentric hammer member rotatable within said housing such that a peripheral portion thereof passes in close proximity to the hole defined by the inner end of said adaptor and having a hollow middle portion capable of admitting the stem end of a vial inserted through said adaptor, means to rotate said hammer member and container means for holding sterilizing liquid removably mounted within said housing and insertable therein into a position such that at least a portion of said hammer member is rotatable therewith.

6. A device as claimed in claim 5 including clamp means to releasably secure a vial stem within said aperture.

7. A device as claimed in claim 6 wherein said clamp means comprises a cup-shaped member mounted for rotation about an axis transverse to said front wall.

8. A device as claimed in claim 7 wherein said adaptor defines a slot in the inner wall thereof and is keyed within said aperture.
